(57) **CLAIM**

The ornamental design for a pneumatic tire, as shown and described.

DESCRIPTION

FIG. 1 is a perspective view of a pneumatic tire incorporating our new design, it being understood that the tread pattern repeats circumferentially throughout the outer circumference.

FIG. 2 is a view of one end of the pneumatic tire shown in FIG. 1.

FIG. 3 is a rear view of the opposite end of the tire.

FIG. 4 is a detail view of FIG. 2.

FIG. 5 is a side view of one side of the pneumatic tire; and, FIG. 6 is a side view of the opposite side of the pneumatic tire.

1 Claim, 6 Drawing Sheets
